UNITED STATES PATENT OFFICE.

ADOLPH C. RECKER, OF OAKVILLE, CONNECTICUT, ASSIGNOR TO WATERBURY MFG. CO.,
OF WATERBURY, CONNECTICUT, A CORPORATION.

FOLDING POCKET GAME-BOARD.

1,266,857.

Specification of Letters Patent.

Patented May 21, 1918.

Application filed December 28, 1917. Serial No. 209,230.

To all whom it may concern:

Be it known that I, ADOLPH C. RECKER, a citizen of the United States, residing at Oakville, in the county of Litchfield and State 5 of Connecticut, have invented a new and useful Improvement in Folding Pocket Game-Boards; and I do hereby declare the following, when taken in connection with the accompanying drawings and the characters 10 of reference marked thereon, to be a full, clear, and exact description of the same, and which said drawings constitute part of this application, and represent, in—

Figure 1 a perspective view of my improved game-board.

Fig. 2 a view of the board shown as open, with a set of checkers nested in one of the complementary checker-containers.

Fig. 3 a view, on an enlarged scale, of one 20 of the flanged cup-like checkers, partly in elevation, and partly in section, shown as "crowned" for use as a "king" by superimposing another checker upon it.

My invention relates to an improved folding 25 pocket game-board designed with particular reference to use by soldiers, the object being to produce at a low cost for manufacture, a simple, compact, convenient and indestructible pocket game-board.

With these ends in view, my invention 30 consists in a folding pocket game-board having certain details of construction as will be hereinafter described and particularly pointed out in the claims.

In carrying out my invention as herein 35 shown, I employ two corresponding flat, sheet-metal leaves 2 and 3 having their adjacent edges formed with interlocking knuckles 4 for the reception of a pintle 5 by means 40 of which the two leaves are hinged together.

It is designed that the inner faces of these 45 leaves shall be marked off into the customary checks or squares of a checker-board, the alternating checks or squares (commonly colored red and black) to be distinguished from each other in any desired manner, as by painting or enameling, or special surfacing of the metal. It will be sufficient for all

purposes of the game, to leave the squares 50 6 in the plain metal and to mark the alternating squares 7 by coloring or enameling them or by engraving or etching, or otherwise differentiating their surfaces, this forming no part of my invention.

The outer edges of the respective leaves 2

and 3 are formed with trough-like semi-circular checker-containers 8 extending through the length of the leaves, parallel with each other, closed at their ends and preferably made integral with the leaves though 60 this is not in any way essential. When the leaves are folded upon each other, the said containers 8 register and form a tubular receptacle for a set of metal checkers 9, the two leaves being then locked together by 65 means of the pivotal clips 10 applied to opposite points on the ends of one leaf and engaging corresponding points on the ends of the other leaf. When the board is opened, as shown in Fig. 2, the checkers will lie 70 either in one or the other of the two checker-containers. When the board is actually in use, the checkers not in place may be held in reserve in either of the containers or distributed between them both. The checkers, 75 as shown, are made by striking up disks of sheet-metal into cup-like form, tapered and flanged. By tapering the cup-like portions of the checkers, I provide for nesting them, and also for "crowning" them, as clearly 80 shown in Fig. 3, to form "kings". The individual checkers are necessarily so small, that unless frictionally held together when "crowned", they would be difficult to use, as the "kings" could not then be picked up as 85 one piece, and as the jostling of the board would endanger the stability of the superimposed checkers forming the "crowns". As shown, the checkers of the two groups, are distinguished from each other by coloring 90 twelve of them black.

My improved game-board, as a whole, is small, light, compact and convenient, and may be easily carried in the pocket or kit of a soldier.

While I have shown and described my improved game-board as a "checker-board", it is obvious that it might be used as a chess-board, as well as for a variety of other games of the same general type. Or, the 100 inner faces of the leaves may be marked off for different games, without altering the mechanical structure of the device. It is also obvious that in place of flanged cup-like checkers, I may employ disks to be marked 105 as chess-men or to be used as checkers. In the use of the word "men", therefore, I wish to be understood as covering any movable pieces to be used in playing games upon my improved folding pocket game-board.

I claim:—

1. A folding pocket game-board comprising two leaves having their adjacent edges hinged together and their corresponding opposite edges formed with complementary half-containers which when the leaves are folded together, combine to form a closed chamber for the storage of the men or pieces used in the game.
- 10 2. A folding pocket game-board comprising two leaves having their adjacent edges hinged together and their corresponding opposite edges formed with semi-circular containers arranged parallel with each other and registering when the leaves are folded together to form a tubular container for the men or pieces used in the game.
- 15 3. In a folding pocket game-board, the combination with two complementary leaves having their inner edges hinged together and their corresponding opposite edges formed with semi-circular checker-contain-

ers, of cup-like flanged checkers adapted to be nested for storage in the said checker-containers.

4. A folding pocket game-board comprising two leaves hinged together and each formed with a complementary semi-circular half-container arranged to combine, on the folding of the leaves together, to form a closed tubular container providing storage for the men or pieces used in the game.

5. A game piece or checker adapted to be nested and to be "crowned" and consisting of a disk of sheet metal struck up into flanged tapering cup-like form.

In testimony whereof, I have signed this specification in the presence of two subscribing witnesses.

ADOLPH C. RECKER.
